UNITED STATES PATENT OFFICE.

PATRICK J. MCINTYRE, OF WATERBURY, CONNECTICUT, ASSIGNOR TO THE NATIONAL COMPANY, OF WATERBURY, CONNECTICUT, A CORPORATION OF CONNECTICUT.

WATER HEATER.

Application filed May 13, 1922. Serial No. 560,735.

To all whom it may concern:

Be it known that I, PATRICK J. MCINTYRE, a citizen of the United States, residing at Waterbury, in the county of New Haven 5 and State of Connecticut, have invented certain new and useful Improvements in Water Heaters, of which the following is a specification.

The invention relates to a water heater, 10 and more particularly to the class of heaters for use in city or suburban homes, barber shops, lunch rooms, drug stores, hospitals, first-aid stations, factories, or at any desired place, where an instantaneous apparatus may be desired.

The primary object of the invention is the provision of a water heater of this character, wherein the construction thereof is novel in form, to enable the operation 20 of the same at a minimum cost and by the use of any type of burner, either gas or kerosene, as the water within the heater can be heated within one minute after the lighting of the burner.

Another object of the invention is the provision of a water heater of this character, wherein the water container is elevated considerably above the burner, and the heat from the latter is conveyed 25 centrally through the container from a chimney supporting the same, which chimney contains a water coil, through which the products of combustion pass, the coil being in communication with the container and is supported in the chimney in a novel manner.

A further object of the invention is the provision of a water heater of this character, wherein the water container is provided with pockets for receiving towels, 40 medical instruments to be sterilized, or food to be kept warm, these pockets being of novel form, so that thorough heating thereof can be had.

A still further object of the invention is the provision of a water heater of this character, wherein the water container has the center exhaust flue for the waste products of combustion constructed to transmit heat 45 from the waste heat that is not taken up by the water coil within the chimney, so as to positively heat the water in the container, causing a circulation in the latter, while this circulation is greatly accelerated by the overflow from an overflow pipe within the 50 container, from which hot water is flowing.

all the time that the heat from the burner is applied to the water coil in the chimney.

A still further object of the invention is the provision of a water heater of this character, which is extremely simple in construction, readily portable, thoroughly reliable and efficient in its purpose, strong, durable, and inexpensive to manufacture.

With these and other objects in view, the invention consists in the features of construction, combination and arrangement of parts as will be hereinafter fully described, illustrated in the accompanying drawings, and pointed out in the claims hereunto appended.

In the accompanying drawings:

Figure 1 is a side elevation of the heater constructed in accordance with the invention and a portion thereof being partly broken away.

Figure 2, is a fragmentary top plan.

Figure 3, is a sectional view on the line 3-3 of Figure 2.

Figure 4, is a vertical longitudinal sectional elevation.

Figure 5, is a fragmentary side elevation of a modified form of a tank or container, the same being broken away or shown partly in section.

Figure 6, is a fragmentary side elevation of the lower portion of the modified form of hot water heater, the same being also partly broken away.

Similar reference characters indicate corresponding parts throughout the several views in the drawings.

Referring to the drawings, in detail, A, designates generally a base, of any desirable style and construction, B, the cylindrical chimney, preferably made from sheet metal, 95 and is supported slightly elevated from the base A, through the medium of legs 5, which are fastened to the latter and also to the lower end of the chimney.

Telescoped into the upper end of the 100 chimney B, is the lower flange portion of a truncated cone shaped flue C, integral with and centrally of a water container or tank D, this flue being extended vertically through the container or tank D, and opens 105 through the top thereof. The flange 6, of the flue C, is fastened to the chimney through the medium of bolts 7, although other means of fastening may be employed.

In the bottom of the container or tank 110

D, are plug nipples 8, in which are fitted removable screw plugs 9, so that in one of the nipples 8, on the removal of the plug, can be engaged a faucet (not shown) so that water may be drained from the container or tank into a basin or other receiver, as the occasion may require, while the other nipple 8, is adaptable for engagement with a water supply pipe leading from 10 a main, should it be desired.

Located within the water container or tank is a water gage tube 10, in which is arranged a float gauge 11, the stem 12, of which works through the top of the container or tank D, to enable a person to determine the water level in the latter.

Mounted in the water tank or container D, opening through the top thereof and depending from the same are cup shaped 20 pockets 13', each having in its side wall a vertical row of spaced openings 13, for the circulation of moisture or heat therein, while closing the pockets at the top of the container or tank are removable covers 14, 25 having hand grips 15, thereon. In these pockets 13, are adapted to be received towels, medical instruments to be sterilized, or food to be warmed.

Within the chimney B, centrally thereof 30 is a copper water coil 16, the upper end of which is tapped into a coupling 17, while the other end portion 18, extends upwardly centrally of the coil 16, to constitute a riser tube, the latter terminating in the upper portion 35 of the flue C, and is engaged in a coupling 19, which has leading from one side of the same an overflow nozzle 20, the same being passed through the flue wall into the water container or tank. Leading 40 from the other side of the coupling 19, is a draw-off tube 21, which extends through the wall of the container or tank B, and has connected therewith a faucet 22, for the discharge of hot water as the occasion requires.

Arranged within the upper portion of the chimney B, immediately below the plane of the bottom of the container or tank D, are opposed water heating coils 23, the adjacent ends of which are engaged in the coupling 17, while the other ends 24, are carried upwardly and laterally through the wall of the flue C, for communication with the container or tank near its bottom.

55 The coils 23, are supported on a cross rod 25, engaged in the chimney B, while the coil 16, is engaged with certain of the fasteners 26, securing the legs 5, to the chimney, and in this manner the coil 16, is supported 60 in the latter.

Resting upon the base A, is a suitable gas or oil burner, 27, of any desirable type, which when lighted heats the coils 16, and 23, it being observed that by reason of 65 the formation of the flue C, the waste heat

conveyed through the chimney, will be transmitted to the container or tank for the heating of the water therein, causing a circulation of the water within the same. This circulation is greatly accelerated by the 70 overflow from the nozzle 20, from which hot water is flowing all the time that the heat is applied to the coils 16 and 23, from the products of combustion from the burner.

In the Figures 5 and 6, there is shown 75 a slight modification of the invention, wherein the water tank or container D, has the coupling 28, at the upper portion of the riser-tube 29, fitted with a removable plug 30, so that said tube can be cleaned and also 80 the coil as pressure may be applied when said plug is removed.

Formed near the bottom of the container or tank is a cylinder 31, which constitutes 85 a guard for the draw-off tube 32, which is tapped at 33, in the offset portion 34, of the riser-tube 29, and this tube 32, has connected therewith the faucet 35, the cylinder prevents cold water from coming into contact with hot water or draw-off tube 32 90 leading to said faucet 35, as will be apparent.

Leading from the coupling 28, is a laterally disposed nipple 36, to which is detachably connected a pipe 37, the same being 95 trained downwardly along the inner wall of the container or tank and terminates close to the bottom thereof so that hot water discharged through said pipe 37, near the bottom of the container or tank mixes with the cold water and starts a vigorous circulation within said container or tank with a result that all of the water becomes hot therein at practically the same time.

In the side wall of the container or tank 100 D, is tapped a removable plug 38, in substitute for plug 9, hereinbefore described.

The cup-shaped pockets 39, in the top of the container or tank D, are formed with foraminous material so that the water may be 110 filtered when poured thereto into the container or tank. This material is only used when the container or tank is not connected to some water system at the point 8, hereinbefore described.

In Figure 6, there is shown the lower portion of the hot water heater and coil 16, has tapped therein and with the riser-tube 18, a T 40, fitted in one arm with a removable plug 41, to permit the cleaning of said coil 120 when occasion may require.

From the foregoing it is thought that the construction and manner of operation of the water heater will be clearly understood, and therefore, a more extended explanation has been omitted.

What is claimed is:

1. A water heater of the character described, comprising a cylindrical chimney portion having a tapered end, supports for 130

- the chimney portion, a water tank surrounding the chimney portion at its upper end, which latter opens through the top thereof, a water coil arranged within the chimney portion and having inlet and outlet ends opening into the water tank, a riser pipe extending upwardly through the chimney portion, a draw off tube connected with the upper end of the riser pipe, and extending laterally through the tank, a discharge faucet connected with the draw off pipe, and means for accommodating articles or food stuff within the water tank.
2. A water heater of the character described, comprising a cylindrical chimney portion having a tapered end, supports for the chimney portion, a water tank surrounding the chimney portion, which latter opens through the top thereof, a water coil arranged within the chimney portion and having inlet and outlet ends opening into the water tank, a riser pipe extending upwardly through the chimney portion, a draw off tube connected with the upper end of the riser pipe and extending laterally through the tank, a discharge faucet connected with the draw off pipe, and means for introducing heat into the chimney portion and cups arranged in the tank.
3. A water heater of the character described, comprising a cylindrical portion having a tapered end, supports for the chimney portion, a water tank surrounding the chimney portion, which latter opens through the top thereof, a water coil arranged with-
- in the chimney portion and having inlet and outlet ends opening into the water tank, a riser pipe extending upwardly through the chimney portion, a draw off tube connected with the upper end of the riser pipe 40 and extending laterally through the tank, a discharge faucet connected with the draw off pipe, means for introducing heat into the chimney portion, a plurality of foraminous cups opening through the top of the tank to 45 form pockets therein, and removable covers for said pockets.
4. A water heater of the character described, comprising a cylindrical chimney portion having a tapered end, supports for the chimney portion, a water tank surrounding the chimney portion, which opens through the top thereof, a water coil arranged within the chimney portion and having inlet and outlet ends opening into the water tank, a riser pipe extending upwardly through the chimney portion, a draw off tube connected with the upper end of the riser pipe and extending laterally 50 through the tank, a discharge faucet connected with the draw off pipe, means for introducing heat into the chimney portion, a plurality of foraminous cups opening through the top of the tank to 55 form pockets therein, and removable covers for the said 60 pockets, and means for permitting the cleaning of the coil and the riser pipe.

In testimony whereof, I affix my signature.

PATRICK J. MCINTYRE.
